UNITED STATES PATENT OFFICE.

DONALD McNICOL, OF NEW YORK, N. Y., ASSIGNOR TO REMINGTON TYPEWRITER COMPANY, OF ILION, NEW YORK, A CORPORATION OF NEW YORK.

TYPEWRITER ATTACHMENT FOR TELEGRAPH SYSTEMS.

Application filed August 23, 1919. Serial No. 319,512.

To all whom it may concern:

Be it known that I, DONALD McNICOL, citizen of the United States, and resident of the borough of Manhattan, city of New York, in the county of New York and State of New York, have invented a certain new and useful Typewriter Attachment for Telegraph Systems, of which the following is a specification.

10 In commercial telegraphy it is quite customary nowadays for the receiving operator to employ a typewriting machine to transcribe the messages as they come in, the messages being usually sent by an ordinary Morse key or by some modification thereof, as for example a semi-automatic sender key. In order that the typewriters may be conveniently used, it is customary also to have especially constructed tables. A table top 15 at the proper height for the sending key is too high for the placement on said top of the typewriter to be used in receiving the messages, and hence it has become necessary to cut away a portion of the table top and 20 provide a sunken platform for the placement thereupon of the typewriter. This platform or baseboard is so situated that the keys of the typewriter come somewhat below the level of the table top, whereby the said keys 25 may be more conveniently manipulated. Moreover, this platform or baseboard is generally in the form of a slide whereby the writing machine may be pulled forward towards the operator and he usually sits with 30 the machine in this forward position while receiving messages. The regular sending key is generally mounted upon the table top some little distance to the rear of this forward position of the operator and in consequence 35 when the incoming message is indistinct or not understood it becomes necessary for the receiving operator to change his position, bend over and reach back to the sending key mounted upon the table top in order 40 to notify the transmitting operator at the other end of the line that it is desired to have him repeat the message from some particular point. Of course after having done this the receiving operator must then re-adjust himself back to receiving position at the typewriter. This is not only time-consuming but 45 is also inconvenient and annoying. My invention has for its main object to provide means whereby it is unnecessary for the receiving operator to change his position or 50

even to remove his hands from the keyboard of the typewriter when he desires to interrupt the incoming message or notify the sender to correct or repeat something that he has passed beyond. To this end I have provided an attachment for the keyboard of the typewriter, which attachment is provided with a supplemental or auxiliary sending key that is connected from the typewriter by suitable wires to the regular sending key located on the table top, and this attachment is also provided with a switch so that the instant anything goes wrong with the incoming message, or the operator fails to understand the signals he may close or 60 open the circuit to the sender, according as a single wire or a multiplexed wire is in use, and signal or telegraph the transmitting operator without the receiving operator changing his position or removing his hands from 65 the keyboard of the typewriter.

To the above and other ends which will hereinafter appear, my invention consists in the features of construction, combinations of devices, and arrangements of parts hereinafter described and particularly pointed out in the claims.

In the accompanying drawings,

Figure 1 represents part of a Remington typewriter, more especially the keyboard portion thereof, with my attachment applied thereto and also connected up to an ordinary Morse sender at a distance.

Figure 2 represents a vertical section, on an enlarged scale, taken at the line *x-x* through the Morse sender, showing more particularly the manner of connecting the typewriter electrically with said sender.

Figure 3 is a vertical section through the attachment on the line *y* of Figure 1 and looking in the direction of the arrow therat and with the switch open.

Figure 4 is a similar view showing the switch closed and the auxiliary sending key depressed or in operation.

Figure 5 is a section on the line *z* of Figure 1, looking in the direction of the arrow therat and showing the switch closed.

Figure 6 is a similar view showing the switch open.

In the various views the same parts will be found designated by the same numerals of reference.

1 represents the forward part of the framework of the typewriter within which

is banked the usual rows of alphabet and numeral keys 2, the case shift keys 3 and the carriage spacing key 4. A row of five keys 5 represents the usual series of tabulator keys present in the Remington machine. My attachment, designated as a whole by the numeral 6, is preferably secured to the right-hand side bar of the typewriter frame and in a manner such that the auxiliary 10 sending key comes within the framework and close to the regular keys of the typewriter. This auxiliary key comprises a hard rubber button or head 7 and a stem 8 carrying at near its lower end a metallic 15 contact piece or head 9. The stem passes through a block of suitable insulating material 10 and said stem is provided with a coiled spring 11 which tends to keep the key normally up, as shown in Fig. 3. The 20 contact piece 9 is preferably provided with a pin 12 which slides in a narrow slot 13 in the insulating block for the purpose of preventing rotation of the key or its stem. The extreme lower end of the stem is attached 25 by a screw 14 to one end of a wire 15 that connects with the regular Morse sender on the table top. The wire 15 passes from said screw up to a metallic connector 16, the eye-portion of which is attached by a screw 17 to a metallic plate or contact 18 embedded in the non-conducting block 10, the screw 17 also serving to hold the plate 18 in position. Said plate 18 forms one element of a switch 30 member, the other element of which consists 35 of a metallic lever 19 pivoted by a screw 20 to the block 10 and provided with a hard rubber key or finger piece 21 which is riveted to the metallic part of the lever, as indicated at 22. A stop pin 23 is provided to 40 limit the outward movement of the switch lever, the bottom end of which rides on the edge of a metallic plate 24 secured by screws 25 to the underside of the insulating block. This plate 24 is provided with a hole at 26 45 for the passage therethrough of the lower end of the stem 8, said hole being larger than the diameter of the stem so that the latter does not touch the plate.

Attached also to the metallic connector 16 50 is another wire 15^a, which may be considered as a continuation of the wire 15. The head of the pivot-screw clamps upon the switch-lever 19 a metallic connector 27, to which is 55 secured a wire 28 that extends to the regular Morse sender on top of the table.

The covered wires 15^a and 28 are brought 60 together and twisted and to the bared end of each wire is soldered or otherwise attached a blade or contact plate 29 of thin spring brass or copper. Between these blades 29 is arranged an insulating strip 30. As shown at Fig. 2 the connector or "wedge" thus formed is adapted to be inserted between the contact points 31 of the main 65 key instrument, one of said contact points

31 being on the under side of the key lever 32 and the other on the base plate 33. In practice, though, I sometimes make the connection to the primary sender by inserting the connector ends under the spring clip 34 70 with which the switch lever 35 co-operates. The main transmitting instrument as a whole is properly connected to the line and ground wires (indicated by 36 and 37) having as customary the usual battery connections, not shown. Neither has it been deemed necessary to illustrate the sounder 75 usually employed in the system.

When the connector is inserted or plugged into the primary sending instrument as shown the current is conducted to the auxiliary key attachment and the circuit may be made and broken by operating the said key, the switch-lever 19 at the attachment and the switch lever 35 at the primary instrument being set as required.

It will be seen that the electrical connections between the main key and the auxiliary key and the line are such that the operator at the typewriter may send a message to the operator at the other end of the line and may also receive a message from the latter. When the switch lever 19 is in the closed position shown at Fig. 5, the operator at the typewriter may receive messages, the current then flowing from wire 28, through lever 19 to contact 18 and through connector 16 to wire 15^a; wires 15^a and 28 being connected to the wires 36 and 37 and to any of the customary sounders in circuit not shown. These sounders may be such as are used in either the single or multiplex operation. When the switch-lever 19 is open as in Fig. 6, then the operator at the typewriter may signal the other operator by actuating the key 7—8. At this time the current traverses wire 28, switch lever 19, base plate 24, wire 15, and wire 15^a, whenever the piece 9 contacts with plate 24 and closes the circuit.

Any suitable means may be provided for securing the auxiliary key instrument to the typewriter. I, however, prefer the simple construction shown which comprises a clamping plate 38 that bears on the outer vertical side of the keyboard frame 1, and is firmly pressed thereagainst by two horizontal screws 39 which enter tapped holes in the block 10. The said clamping plate at its upper portion is formed with a horizontal flange 40 that bears upon the top edge of the frame bar 1, and said flange is extended over onto the top of the insulating block 10, and secured thereto by two vertical screws 41 whose threaded ends enter tapped holes in said block. Said screws pass through plain holes in said flange and the latter is cut away between said holes so that it may be clear of the key stem and its spring. Owing 120 to the flanged formation 1^a of the frame-

bar the block 10 is cut away or recessed to match so that the outer side of the block lies flush with the inner face of the frame side bar.

5 If it be desired at any time to use the main key the connector must be withdrawn from between the contacts 29, 29, or from under the spring clips 34, as the case may be.

10 Whenever it may be desired to shift the typewriter to another table or place the connector is also withdrawn from the main key rather than disengage the attachment from the typewriter. In many instances the typewriters belong to the operators and accordingly they take or move the machines 15 with them wherever they may have to go.

20 My attachments are made to fit or be applied to existing machines and to be sold to operators thereof, though of course they may be applied to newly made machines and sold therewith.

What I claim as new and desire to secure by Letters Patent, is:—

25 1. An auxiliary telegraph key attachment comprising an insulating block, a clamping means for securing said block to the side bar of a typewriter frame, a hand operated transmitting key slidable in said block and provided with a contact device near its 30 lower end, a contact plate on the under side of said block and perforated for the passage therethrough of the lower end of said key, a wire connected to the lower protruding end of said key and extending to a switch 35 contact secured to said block, a switch lever

pivoted to said block and adapted for movement to and from said last mentioned contact, said switch lever at its lower end being also adapted for contact with said plate at the under side of said block, a second wire 40 connected to said switch contact, and a third wire connected to said switch lever, said second and third wires being adapted for connection with a telegraphic line circuit.

2. An auxiliary telegraph key attachment 45 comprising an insulated block, means for securing said block to the side bar of a typewriter frame, a transmitting key having a stem that passes vertically through a hole in said block and through a hole in a metallic 50 contact plate at the under side of said block, a contact device on said stem adapted when the key is depressed to contact with the plate on the under side of the block, a switch lever pivoted at the side of said block, a contact for said lever embedded in the side of said block, an electric connection between the lower protruding end of said stem and said embedded contact device, an electric connection between the latter and the line 55 wires, and an electric connection between the switch and the line wires.

Signed at the borough of Manhattan, city of New York, in the county of New York and State of New York, this 21st day of Au- 60 gust, A. D. 1919. 65

DONALD McNICOL.
